UNITED STATES PATENT OFFICE.

SAMUEL T. ATKIN AND OLIVER STEELE, OF GEORGETOWN, TEXAS.

WELL-BUCKET FIXTURE.

SPECIFICATION forming part of Letters Patent No. 349,626, dated September 21, 1886.

Application filed June 10, 1886. Serial No. 204,753. (No model.)

To all whom it may concern:

Be it known that we, SAMUEL T. ATKIN and OLIVER STEELE, citizens of the United States of America, residing at Georgetown, in the 5 county of Williamson and State of Texas, have invented certain new and useful Improvements in Well-Bucket Fixtures, of which the following is a specification, reference being had thereto in the accompanying drawings.

This invention pertains to well-bucket fixtures; and its object is to provide for the ready opening of the valve for entrance into the bucket of water or other fluid, and the closing of the same when the said bucket has been sufficiently supplied; also securely to hold the parts together as against loosening in consequence of frequent usage; and it consists in the detailed construction, combination, and arrangement of the parts, substantially as hereinafter fully shown and described, and particularly pointed out in the claims.

In the accompanying drawings, Figure 1 is a vertical sectional elevation of our invention. Fig. 2 is a similar view showing the valve 25 opened. Fig. 3 is a plan view; and Fig. 4 is a cross-sectional view on the line *xx*, Fig. 1.

In carrying out our invention we provide a sheet-metal cylinder or barrel, A, of suitable length, which, at its upper end, is provided with a top, B. Said top consists of an annular ring provided with a flanged portion, *a*, for fitting within and around said cylinder or barrel, and a cross-bar, *b*, integral therewith, which cross-bar at its widened or central portion has an aperture formed therein for the purpose hereinafter explained.

C is an annular bottom, also provided with a flanged portion for securely retaining the same in position with the lower end of the cylinder or barrel, to which it is secured by solder, as also the annular ring forming the top B. This annular bottom is provided with two semicircular openings or apertures, *b'*, near the center thereof, a suitable portion or space, *b''*, being left in said bottom between said openings or apertures, and to the upper side of said portion or space is rigidly secured thereto, at about its center, one end of an approximately oblong connecting-bar, *b³*, which bar is apertured at its 50 center near the upper end thereof.

D is the valve, which consists, preferably, of two parts or portions, the upper part or portion

being made of metal and the lower part or portion of sheet rubber or packing. The valve D is designed to rest on the inner surface of 55 the annular bottom and extend at each end slightly beyond the sides of each semicircular opening, or aperture *b'* of said bottom. This valve is provided with a longitudinal slot or opening through which the connecting-bar *b³* 60 is passed, said connecting-bar serving as a guide for the valve.

The valve D is apertured at about the center of that portion thereof immediately over the openings or apertures *b'*, for passage there- 65 through of the screw-threaded ends of an approximately U-shape clip, E, the ends of which, after having been passed through the said ap- 70 pertures of the valve, are provided with nuts for securely retaining the ends of said clip in po- 75 sition with the valve. Through the apertures formed in the connecting-bar *b³* is passed the hooked end of a connecting-rod, F, which is screw-threaded on its upper end, and on said end of the rod F is passed the horizontal cross- 80 bar of a bail or "rope loop," which bar is pro- 85 vided on its under surface with a flanged portion for insertion in the aperture formed in the center of the cross-bar *b*, and after-said bail or rope loop is placed in position the nut *d* is 90 screwed on the end of said rod, thus securely retaining the same in position. From this it will be seen that by tightening the screw *d* on the connecting-rod F the top B, bottom C, and the cylinder or barrel A will all be securely 95 held in position, and that by the use of the said connecting-rod very little solder is required to secure said parts together.

In operation the suspending rope or chain is connected to the bail or rope loop and the 90 normal position of the valve D is that shown in Fig. 1. When the well-bucket is lowered into the well or cistern, the U-shaped clip (which we term the "valve-opener") will, upon striking against any surface, cause the valve to 95 open and permit ingress or passage of the wa- 100 ter through the semicircular openings or apertures of the annular bottom C, and when a sufficient quantity of water or other fluid (as the case may be) is obtained in the cylinder or barrel the said valve will close by gravity, and be thus held by the weight of the water contained in said cylinder or barrel.

Having thus fully described our invention,

what we claim, and desire to secure by Letters Patent, is—

1. The herein-described well-bucket, comprising the cylinder or barrel, the flanged top provided with an apertured cross-bar, the annular bottom having semicircular apertures, the apertured connecting-bar, the hooked connecting-rod, the bail or rope loop, the valve and the valve opener, substantially as shown and described.

2. The combination, with the cylinder or barrel, the top having an apertured cross-bar and the apertured bottom, of the hooked connecting-rod, the apertured connecting-bar, and the bail or rope loop, substantially as shown and described.

3. The combination, with the cylinder or barrel, the top secured thereto, and the aper-

tured bottom, of the valve, the valve-opener, the connecting-rod having one end provided with a hook and the other end with a screw-thread, the apertured connecting-bar, the bail or rope loop, and the nut fitted on said connecting-rod, substantially as shown and described.

4. The combination, with the barrel or cylinder, and the valve and its opener, of the annular bottom having semicircular openings or apertures, substantially as shown and described.

In testimony whereof we affix our signatures in presence of two witnesses.

SAMUEL T. ATKIN.
OLIVER STEELE.
